UNITED STATES PATENT OFFICE.

LESLIE H. BURLIN, OF CHICAGO, ILLINOIS, ASSIGNOR TO BURLIN CO., A FIRM COMPOSED OF LESLIE H. BURLIN AND WALTER H. SEDGWICK, OF CHICAGO, ILLINOIS.

DESIGN FOR AN UPRIGHT MEMBER FOR A LAMP OR SIMILAR ARTICLE.

Application filed October 10, 1925. Serial No. 15,090. Term of patent 7 years.

To all whom it may concern:

Be it known that I, LESLIE H. BURLIN, a citizen of the United States of America, residing at Chicago, in the county of Cook and State of Illinois, have invented a new, original, and ornamental Design for an Upright Member for a Lamp or Similar Article, of which the following is a specification, reference being had to the accompanying drawing forming a part thereof, and in which—

Fig. 1 is a side view and Fig. 2 is an edge view of an upright member for a lamp or similar article, showing my new design.

My upright member for a lamp or similar article is made and sold as a complete and separate article of manufacture.

I claim:

The ornamental design for an upright member for a lamp or similar article, as shown.

LESLIE H. BURLIN.
